UNITED STATES PATENT OFFICE

2,672,587

CATHODIC PROTECTION OF TANK
BOTTOMS

Scott P. Ewing, Tulsa, Okla., assignor to Standard
Oil Development Company, a corporation of
Delaware

Application November 15, 1952, Serial No. 320,660

2 Claims. (Cl. 324—62)

1

The present invention is concerned with an improved method of cathodically protecting a tank bottom from galvanic corrosion. The invention is more particularly concerned with an improved method of determining soil resistivities adjacent to tanks for the purpose of determining the current required for cathodic protection of such tanks. In accordance with the specific adaptation of the present invention a plurality of electrodes are utilized at critically spaced distances from the tank which distances are a function of the diameter of the tank bottom.

It is well known in the art to protect metallic tank bottoms from galvanic corrosion by various procedures. For instance, a widely used method for preventing corrosion of buried or submerged metallic structures is to make the structure electrically cathodic to the surrounding medium by causing current to flow from an external anode to the structure. Under these conditions corrosion is prevented providing the current density on every part of the metallic tank bottom structure exceeds a certain minimum which depends on the metal and the surrounding medium. In general when a steel tank bottom is exposed to salt water it is desirable to have a current density at the center of the tank in the range from about 4 to 5 milliamperes per sq. ft. On the other hand in most soils a current density in the range from about 1 to 3 milliamperes per sq. ft. is sufficient.

Heretofore in the art it was known that the current density at every part of a metallic disc can be determined when the medium surrounding the disc is of uniform resistivity and there is no polarization of the disc. (Smythe, "Static and Dynamic Electricity," McGraw Hill, p. 114 (1950)). For instance it is known that the point of lowest current density of a metallic disc is the center of the disc where the current density is $\frac{1}{2}$ the average current density on the entire disc.

However, many anomalies exist with respect to the surrounding earth medium on which a tank bottom is positioned. For instance it is well known that the resistivity of the earth is not uniform, there being variations with depth as well as with horizontal direction. However the variations with depth are much greater than variations in the horizontal direction. Thus heretofore in the art if a current density was to be determined with respect to the center of a tank bottom it was either necessary to empty the tank and cut through the plates on the tank bottom or to tunnel under the tank or to guess at the current density at the center.

The present invention is thus particularly con-

2

cerned with an improved method of determining the current density on the external central part of the tank bottom when a known current is caused to flow through the earth from an external anode to the tank. The present invention utilizes a plurality of critically spaced electrodes the spacing of which is a function of the diameter of the tank bottom.

The process of the present invention may be more fully appreciated by reference to the drawings illustrating embodiments of the same. Figures 1 and 2 illustrate resistivities measured in ohm ft. with regard to various spanning distances of electrodes. Figure 3 illustrates the efficiency of current distribution on a metallic disc as determined from various experimental runs, the efficiency being defined as the ratio of the current density at the center to the average current density on the disc. Figure 4 illustrates the means for determining the current density at the center of the tank bottom in accordance with the present invention.

Referring specifically to Figure 1 it is noted that as the span between the electrodes increases, the resistivity decreases. This simply means that as the span between electrodes increases, the average depth of the electrical flux extends into lower substrata of higher conductivity. Here there exists a condition where the upper thin stratum of the earth's surface has a lower conductivity than the lower substrata of the earth's surface. This is one condition encountered in determining the current density at the center of the tank bottom. On the other hand Figure 2 illustrates a condition wherein as the span between the electrodes increase the resistivity increases. This indicates a condition wherein the upper thin surface of the earth's strata has a relatively high conductivity and wherein the lower substrata have a lower conductivity.

Figures 1 and 2 thus show that for the purpose of the present invention the earth may be considered to consist of a more or less thin surface layer of one resistivity which is underlain to great depth by a substrata medium of another resistivity.

Referring specifically to Figure 3 a number of experimental tests were made employing a tank model which in one set of runs was positioned over a Bakelite substratum and in another set of runs over a copper substratum. The model was constructed so that it was possible to measure the applied current density at numerous points including its center and thus determine the efficiency of current distribution. Measurements

were also made to determine the apparent resistivities ρ_1 and ρ_2 for various water depths over Bakelite and copper substrata. The results of these tests are illustrated in Figure 3.

It is evident that when ρ_2 equals ρ_1 the abscissa becomes zero and the efficiency is 50% (that is uniform resistivity in the earth's substrata). However when the resistivity of the lower substrata increases the efficiency will decrease below 50%. On the other hand if the resistivity of the earth's substrata decreases the efficiency will rise above 50%. Referring specifically to Figure 4 the potential difference E between two points at distances r_1 and r_2 from the center of a small spherical electrode discharging current I in a uniform medium of resistivity ρ is

$$E = \int_{r_1}^{r_2} \frac{I \rho dr}{4\pi r^2} = -\frac{I \rho}{4\pi} \left(\frac{1}{r_2} - \frac{1}{r_1} \right) \quad (1)$$

If the limits are chosen so that $E=0$ when $r_2 \rightarrow \infty$ and where the medium is changed to semi-infinite then

$$E = \frac{I \rho}{2\pi} \frac{1}{r} \quad (2)$$

In the four electrode method of resistivity measurement the electrodes are arranged in a straight line with a distance a between adjacent electrodes. The outer electrodes 1 and 4 are chosen as current electrodes and the inner electrodes 2 and 3 are the potential electrodes. This is illustrated below.

Then the potential difference between 2 and 3 produced by a positive current I at 1 and a negative current I at 4 is as follows:

$$\begin{aligned} E_{(2-3)} &= \frac{I \rho}{2\pi a} - \frac{I \rho}{2\pi(2a)} - \left(\frac{I \rho}{2\pi(2a)} - \frac{I \rho}{2\pi a} \right) \\ &= \frac{I \rho}{2\pi} \left(\frac{1}{a} - \frac{1}{2a} - \frac{1}{2a} + \frac{1}{a} \right) \\ &= \frac{I \rho}{2\pi} \frac{1}{a} \end{aligned} \quad (3)$$

Now the resistance

$$R_{(1-4)(2-3)} = \frac{E_{(2-3)}}{I_{(1-4)}} = \frac{\rho}{2\pi a}$$

or

$$\rho = 2\pi a R \quad (4)$$

Similar to the development indicated in Equation 2 it can be shown that the potential at a point located a distance a from the center of a conducting disc of radius r and discharging a current I is:

$$E = \frac{I \rho}{2\pi} \frac{1}{r} \sin^{-1} \frac{r}{a} \quad (5)$$

("Earth Conduction Effects in Transmission Systems," E. D. Sunde, D. Van Nostrand Co., Inc., N. Y., p. 44, 1949.)

It should be noted that this relationship holds true only in the plane of the disc.

Now if the disc is substituted for one current electrode in the four electrode method of resistivity measurement as schematically illustrated by Figure 4.

Then the potential drop from the disc to electrode 2 can be expressed as follows:

$$E_1 = \frac{I \rho}{4} - \frac{I \rho}{2\pi r} \sin^{-1} \left(\frac{r}{3r+b} \right) - \frac{I}{2\pi r} \sin^{-1} \left(\frac{r}{r+b} \right) + \frac{I \rho}{4\pi r} \quad (6)$$

Similarly the potential drop between electrodes 2 and 3 can be expressed as follows:

$$E_2 = \frac{I \rho}{2\pi} \left[\left(\frac{1}{r} \sin^{-1} \left(\frac{r}{r+b} \right) - \frac{1}{r} \sin^{-1} \left(\frac{r}{2r+b} \right) + \frac{1}{2r} \right) \right] \quad (7)$$

Now if b is so chosen so that $E_2 = E_1$ it is found that the distance $b = 0.3225r$ and the resistances

$$R_1 = R_2 = \frac{0.91 \rho}{2\pi r} \quad (8)$$

The above expression is true only in a medium of uniform resistivity. Since actual soil resistivities vary with depth, and coatings may be present on the tank bottom, R_1 and R_2 will in general be different. It is therefore convenient to define R_1 and R_2 in terms of two apparent resistivities as follows:

$$\rho_1 = \frac{2\pi R_1}{0.91} \quad \text{when } R_1 = \frac{E_1}{I} \quad (9)$$

and

$$\rho_2 = \frac{2\pi R_2}{0.91} \quad \text{when } R_2 = \frac{E_2}{I} \quad (10)$$

Thus it is evident that if the current density on the center of a tank bottom is thereby determined this can be readily accomplished by the positioning of three external electrodes. The first electrode will be positioned .3225 tank diameters from the tank. The second electrode will be positioned one tank diameter from the first electrode while the third electrode will be positioned in a straight line one tank diameter from the second electrode.

The operation current is applied between the tank and the third electrode. The potential change produced by this current is measured between the tank and the first electrode and between the first and second electrode. These potential changes are designated as E_2 and E_1 respectively. The efficiency is then determined in accordance with the procedure described heretofore.

While the above procedure has been described for the determining of current density on a non-coated disc or tank bottom, it is to be understood that the procedure is equally applicable for the determining of current density on coated discs or tank bottoms. Thus the method is very applicable for efficiently determining the resistance of the coating.

The present invention may be more fully understood by the following example illustrating the same:

Example

Due to soil conditions it was necessary to apply 5 milliamperes per sq. ft. at the center of the bottoms of tanks A and B.

With respect to tank A it was determined that

$$\frac{R_2 - R_1}{R_2 + R_1} \text{ was minus .2}$$

From Figure 3 it is evident that the efficiency was 20%.

With respect to tank B it was determined that

$$\frac{R_2 - R_1}{R_2 + R_1} \text{ was .3}$$

From Figure 3 it is evident that the efficiency with respect to tank B was 80%.

The bottom of each tank had an area of approximately 10,000 sq. ft., meaning that approximately 50,000 milliamperes would have to be supplied, assuming the current density to be uniform and the efficiency to be 100%.

5

Thus it is evident that with respect to tank A having a 20% efficiency it is necessary to supply 250 amperes while with respect to tank B with 30% efficiency, it is necessary to supply 62.5 amperes.

Having described the invention, it is claimed:

1. Improved process for determining the current necessary to be supplied to a metallic disc positioned on any type of earth surface to secure a predetermined current density at the center of said disc, which comprises positioning on said earth surface an initial electrode a distance of .3225 diameters from said disc, positioning a second electrode one disc diameter from said initial electrode, positioning a third electrode one disc 15 diameter away from said second electrode, all

6

electrodes being on the projection of a tank radius, causing current to flow between said structure and between said outer electrode, measuring the potential change produced between said disc and said first electrode, and between said first and said second electrode, designating these resistances as R_2 and R_1 , respectively and determining the relationship of $(R_2 - R_1)$ over $(R_2 + R_1)$ and determining the efficiency, whereby the total 10 amount of current necessary to be furnished is determined.

2. Processes defined by claim 1 wherein said disc comprises a tank bottom.
